UNITED STATES PATENT OFFICE.

GEORGE J. KILB, OF COVINGTON, KENTUCKY, ASSIGNOR TO UNITED SHOE MACHINERY COMPANY, OF PATERSON, NEW JERSEY, A CORPORATION OF NEW JERSEY.

MACHINE FOR OPERATING ON INSOLES.

1,243,951.

Specification of Letters Patent.

Patented Oct. 23, 1917.

Application filed February 8, 1913. Serial No. 747,042.

To all whom it may concern:

Be it known that I, GEORGE J. KILB, a citizen of the United States, residing at Covington, in the county of Kenton and 5 State of Kentucky, have invented certain new and useful Improvements in Machines for Operating on Insoles; and I do hereby declare the following to be a full, clear, and exact description of the invention, such as 10 will enable others skilled in the art to which it appertains to make and use the same.

The present invention relates to machines for operating on insoles which are used in 15 the manufacture of boots and shoes, and more particularly to machines for applying reinforcing fabric to insoles.

At the present time there are three types of machines for applying reinforcing fabric 20 to insoles, namely; (1) machines for forming a bead or crimp in the reinforce and securing it to the insole, commercially known as "gemming machines;" (2) machines for preliminarily tucking the material into the inside angle at the base of 25 the lip, prior to the gemming operation, known commercially as "forming-in machines;" and (3) machines for tightening the reinforcing material about the lip of 30 the insole, subsequent to the gemming operation, known commercially as "rib-tightening machines."

The object of the present invention is to 35 improve the construction and operation of machines for applying reinforcing fabric to insoles, adapted particularly to perform the rib tightening operation, although, as will be recognized by those skilled in the art from the following description, certain 40 features of the invention are not limited to use in a machine for performing a rib tightening operation but may advantageously be employed in other types of machines for applying reinforcing fabric to insoles. 45 Also certain other features of the invention may advantageously be employed in machines for operating on lipped insoles other than machines for applying reinforcing fabric thereto.

To the accomplishment of this object and such others as may hereinafter appear, the features of the invention relate to certain devices, combinations and arrangements of parts, hereinafter described and then set forth broadly and in detail in the appended

claims, which possess advantages readily apparent to those skilled in the art.

The various features of the present invention will be best understood from an inspection of the accompanying drawings 60 illustrating the preferred embodiment of the invention, in which:

Figure 1 is a right side elevation of the machine;

Fig. 2 is a detail in right side elevation 65 showing the position of the parts during the operation of the machine and after the lip of the insole has been turned inward;

Fig. 3 is a detail in right side elevation of the devices for adjustably carrying the 70 ironing tool;

Fig. 4 is a front elevation;

Fig. 5 is a sectional plan on the line 5—5, Fig. 4;

Fig. 6 is a sectional elevation on the line 75 6—6, Fig. 4;

Fig. 7 is a detail in plan showing the reinforcing fabric trimmed on the feather, at the shank, along a line located within the edge of the insole;

Fig. 8 is a detail in right side elevation showing the lip being ironed into its final angular form; and Fig. 9 is a transverse section through the working portion of the ironing tool on the line 9—9 of Fig. 8. 85

In the embodiment of the invention illustrated in the drawings the work support, upon which the unribbed or grain side of the insole rests while it is being operated upon, consists of a roll 1 mounted upon the 90 forward end of a horizontal shaft 2 journaled in stationary bearings 3 formed in standards 4 and 5 projecting upward from a plate 6 carried by bench legs 7. The work support is positively driven during 95 the operation of the machine through a gear 8 carried by the shaft 2 and engaged by a pinion 9 carried by a stub-shaft 10. The shaft 10, carrying the fast and loose pulleys 11 and 12, is driven from a suitable source 100 of power through a belt drive. The belt is shifted from one pulley to the other, by hand, in the usual manner. In order to permit the position of the pulleys to be varied 105 to meet different conditions in different factories the shaft 10 is journaled in the lower end of an arm 15 projecting from a hub 16 rotatably mounted on a hollow bearing 16^a projecting from the standard 5 about the shaft 2 and secured thereto by a set screw 110

17. By loosening the set screw the position of the pulleys may be changed by swinging them about the shaft 2.

The devices for operating on the insole supported on the work support to tighten the previously applied reinforcing fabric into the angles at the base of the lip consist of an inside tightening tool comprising a disk 18 arranged to press the reinforce into the inside angle at the base of the lip, and an outside tightening tool comprising a rotary wheel 19 arranged to press the reinforce into the outside angle at the base of the lip. The wheel 19 also coöperates with the roll 1 in feeding the insole through the machine.

The disk 18 is provided with a slightly convex bottom 20 for engaging the face of the insole adjacent the lip, a peripheral edge 21, for tucking the reinforcing fabric down into the inside angle at the base of the lip, and a reduced stem 22 which permits the bending of the upper portion of the lip inwardly in the manner hereinafter described. The reduced stem 22 is formed on the lower end of a block 23 which is secured to the lower end of a hollow spindle 24 by means of an elongated rod (not shown), carried by the block 23, and a nut 25 threaded upon the upper end of the rod and arranged to engage the upper end of the spindle 24. The spindle 24 is provided at its opposite ends with frusto-conical shoulders 26, each of which rotates, during the passage of the insole through the machine, on a ball bearing 27 carried in a race 28 formed in each end of a thimble 29 carried by a tubular sleeve 30. The thimble 29 is forced downwardly so as to press the disk 18 firmly against the face of the insole by a spring 31 coiled around the thimble and interposed between a peripheral shoulder 32 formed on the thimble and a knurled cap 33 threaded for adjustment upon the exterior of the sleeve 30. In order to limit the downward movement of the disk 18 under the influence of the spring 31, the sleeve 30 is provided with a circular seat 34 for the shoulder 32 on the thimble. In order to permit the position of the disk 18 to be varied as desired the sleeve 30 is loosely carried by a cylindrical block 35 in a casing 36. The block 35 is provided with a stem 37 rotatably mounted in a split clamp 38. The clamp 38 is slidably mounted on a horizontal rod 39 projecting from an arm 40 adjustably secured by a nut 41 to a frame 42 pivotally mounted at 43 to the standard 5. With this construction the disk 18 may be adjusted toward and from the face of the insole by sliding the sleeve 30 in the cylindrical block 35, toward and from the outside tightening tool 19 by rotating the block 35 in the clamp 38, inclined in the line of feed by rotating the arm 40 on the frame 42, and inclined 65 across the line of feed by adjusting the posi-

tion of the block 35 in the clamp 38 and sliding the clamp 38 along the rod 39. The inside tightening tool 18 may also be advanced or retracted in the line of feed relatively to the outside tool by a combination of some of these adjustments. In order to provide a single means for holding the sleeve 30 in adjusted position in the block 35, for holding the block 35 in its casing 36 in adjusted position on the clamp 38, and for holding the clamp 38 in adjusted position on the rod 39, the stem 37 on the block 35 is threaded to support a butterfly nut 44. Rotation of this butterfly nut frees or clamps the parts hereinbefore referred to at the will of the operative.

The wheel 19 is secured on the lower end of a stub-shaft 45 which is rotatably mounted in a bearing 46 formed on the frame 42. The wheel 19 is positively driven during the operation of the machine from a counter shaft 47, journaled in the frame 42, through bevel gears 48 and 49 carried respectively by the shafts 45 and 47. The counter shaft 47 is driven from the main shaft 2 through a train of gears 50. The wheel 19 is provided with a frusto-conical portion, the face 51 of which is arranged to engage the reinforcing fabric on the feather of the insole and coöperate with the work supporting roll 1 in feeding the insole through the machine. This portion of the wheel 19 is arranged with the peripheral edge 52 of its larger base in engagement with the outside angle at the base of the lip. As the face 51 is provided with teeth, to aid in the feeding of the insole, the edge of the face in contact with the outside angle at the base of the lip is serrated. This saw-like edge acts to firmly press the reinforcing fabric down into the angle at the base of the lip, consolidates the material at the base of the lip, and produces a sharp corner where the lip begins to rise from the face of the insole.

The face 51 of the wheel 19 is also arranged so that, when in working position, its feather engaging surface inclines toward the edge of the insole. The work supporting roll 1 is preferably beveled as at 53 so that its feather supporting surface is substantially parallel to the feather engaging surface 51 of the wheel 19. With these parts thus constructed and arranged they will act to mold the feather down at an angle to the body of the insole and impart a "dish" to the unribbed face of the insole in the manner shown in Fig. 2. It is important that the insole be dished in the manner described at the time the rib is tightened for the reason that if the insole is left flat on its unribbed face the transverse bending necessarily imparted to the insole when assembling it on the last will loosen the fabric at the base of the lip and the good effect of the rib tightening operation will thus be nullified.

5 fied. The dishing of the insole provides for fitting the bottom of the last without undue strain on the fabric. The roll 1 may also be provided with a comparatively greater beveled portion 54. By arranging the work support with this bevel 54 beneath the feather of the insole, and associating therewith a wheel 19 having a feather engaging face parallel to the bevel 54, a greater dish, as is desirable in some styles of shoes, may be imparted to the insole.

10 I have discovered that if the base and upper portion of the lip stand substantially perpendicular and parallel respectively to the face of the insole that when the sole is bent transversely to the curved bottom of the last in the assembling operation, the lip will then stand at the proper angle to the bottom of the last for the convenient and proper lasting and sewing of the shoe. That is, a substantially right-angular bend at the upper portion of the lip will provide an excellent abutment for the channel guide of the welter and will so stiffen the lip that it 15 will not be knocked out of shape in the lasting operation. In order to bend and set the upper portion of the lip inwardly substantially parallel to the face of the insole, the wheel 19 is provided with a vertical face 55 arranged to engage the lower portion of the outer side of the lip and with a face 56 arranged substantially perpendicular to the face 55 to engage the upper portion of the outer side of the lip. With this construction 20 the base and upper portion of the reinforced lip are acted on in such manner as to cause such portions to stand substantially perpendicular and parallel respectively to the face of the insole. By mounting the disk 18 on a reduced stem a support is provided for the inside surface of the lip which coöperates 25 with the faces 55 and 56 in shaping the lip into the desired form.

30 After the upper portion of the lip is bent inwardly it is desirable to iron the bent lip after it is removed from the influence of the tools 18 and 19 in order to set it in its final form with sharp, unbroken edges, and insure that it will remain permanently bent 35 inward. To this end an ironing tool, comprising a bar 57, projects over the lip across the line of feed (Fig. 8). This tool projects from an arm 58 which has a shoulder 59 (Fig. 4). The shoulder 59 is bolted to one 40 end of a lever 60 centrally pivoted on the bearing 46 (Fig. 3). The lever 60 is normally actuated in one direction by a spring 61, interposed between the top of the support 46 and the bottom of the lever. The 45 tension of the spring and the position of the lever are controlled by suitable adjusting and locking screws 62. The tool 57 is normally adjusted so that it extends beneath the face 56 of the wheel 19, at the rear of the 50 tool 18, in the manner shown in Figs. 8

5 and 4. As shown in Figs. 4 and 9 the work engaging face of the tool 57 is beveled, with its beveled edge directed toward the forming tools, so that the rib may easily pass beneath it and the upper portion of the rib 70 may be additionally bent after the rib passes from the influence of the face 56 on the wheel 19. The purpose of bringing the lip to substantially the form shown in Fig. 8 is to provide a well defined lower portion to receive the thread in the inseaming operation, and by the sharp corners and edges preserve the position of the lip after the inseam trimming operation.

75 As is well known to those skilled in the art, it is desirable in the operation of insole machines to permit of increased speed, that the points of operation of the tools be transferred around the various curvatures of the insole without attention on the part of the operative except to insert the insole into the machine and remove it therefrom at the completion of the operation. In the present machine this result is accomplished by oppositely engaging the rib of the insole in advance of the point of operation of the insole feeding face 51 of the wheel 19. The rib is engaged on its inside by the inside tightening tool 18. On its outside the rib is engaged by a guide 63 80 which is mounted for vertical adjustment on the bearing 46. The guide 63 is curved to extend beneath the face 56 in proximity to the wheel 19 so that its operating portion may extend over the feather and engage the rib at the proper point.

85 It is desirable, from a selling point of view, that a portion of the reinforcing fabric be removed from above the outer margin of the feather at the shank portion 90 at least. The preferred manner of accomplishing this is by trimming the fabric at the shank along a line located within the edge of the insole. In the illustrated embodiment of the invention a trimming knife 95 100 is formed on the end of a cylindrical shank 65 arranged substantially parallel to the surface of the insole. The shank is secured by a set screw 66 to a split block 67 arranged to be clamped by means of a butterfly nut 68 to the horizontal arm of a bent rod 69, the vertical arm of which is secured to a bracket 70 projecting from the standard 4, by means of a bolt 71. With this construction the knife may be adjusted 105 longitudinally by shifting the shank 65 in the block 67, laterally by shifting the block 67 on the horizontal arm of the rod 69, and vertically by shifting the rod 69 in the bracket 70. As heretofore pointed out, it 110 is desirable, particularly at the shank of the insole, to trim off or otherwise position the edge of the reinforcing fabric within the edge of the insole. In the illustrated embodiment of the invention, in operating 115

upon a particular size of insole the knife 64 is adjusted preferably, although not necessarily, so that it just clears the edge of the insole around the forepart. As the 5 width of the feather is greater at the shank than it is around the forepart of the insole, it is evident that with this arrangement of the knife the reinforcing fabric will be trimmed along a line on the feather, at the 10 shank, within the edge of the insole as its point of operation is transferred along the shank of the insole. The result obtained is 15 illustrated by Fig. 7.

The rib tightening tools are held down 20 upon the work by means of a spring 72, one end of which is connected to a hook 73 on the plate 6 and the other end of which is connected to a pin 74 carried by the frame 42. The pin 74 may be vertically adjusted 25 in the frame 42 to vary the tension of the spring 72 by a butterfly nut 75. In order to elevate the frame 42 to permit the ready removal and insertion of the insole the standard 4 carries a centrally pivoted lever 76, one end of which is connected to the frame 42 by a link 77 and the other end of which is connected to a treadle (not shown) by a treadle rod 78.

Preferably the rib tightening tools, as 30 well as the lip ironing tool, are heated, as it has been found that the lip is better turned and acquires a more permanent shape if the operations are performed with the tools at an elevated temperature. The heat 35 of the tools also renders the reinforcing fabric correspondingly more plastic and pliable. The application of heat may be by means of a gas flame such as is used for heating the tools of stitch wheeling and 40 other machines for operating on shoe soles.

It will be understood that the specific 45 construction and arrangement of the parts is not material to the broader features of the invention and may be varied and modified without departing from the invention.

What is claimed as new, is:—

1. A rib tightening machine for reinforced 50 insoles, having, in combination, an inside fabric tightening tool, an outside fabric tightening tool, and means for relatively adjusting the tools in the line of feed, substantially as described.

2. A rib tightening machine for reinforced 55 insoles, having, in combination, an inside fabric tightening tool, an outside fabric tightening tool, and means for adjusting the inside tool in the line of feed, substantially as described.

3. A rib tightening machine, having, in 60 combination, an outside fabric tightening tool, and a universally adjustable inside fabric tightening tool, substantially as described.

4. A rib tightening machine for reinforced 65 insoles, having, in combination, an inside

fabric tightening tool, an outside fabric tightening tool, and means for varying the relative vertical, lateral and angular positions of said tools, substantially as described.

5. A rib tightening machine for reinforced 70 insoles, having, in combination, an inside fabric tightening tool, an outside fabric tightening tool, means for varying the relative vertical, lateral, and angular positions of said tools, and a single means for maintaining the tools in their desired adjustment, substantially as described.

6. A rib tightening machine for reinforced 75 insoles, having, in combination, a work support, and a plurality of coöperating means 80 for compressing the reinforcing fabric at the base of the rib and for bending the upper portion of the rib inward substantially parallel to the face of the insole, substantially as described.

7. A machine for preparing reinforced 85 insoles having reinforcing fabric beaded about the lip and extending across the entire width of the feather, having, in combination, means for supporting and feeding the insole; and 90 means for bending the lip and feather of the insole away from each other, for forcing the reinforcing fabric into the angle of the lip and feather, and for positioning the edge of the fabric within the edge of the insole, substantially as described.

8. A machine for applying reinforcing 95 fabric to an insole, having, in combination, means for supporting and feeding the insole and for operating upon the reinforcing fabric 100 at its marginal portion, and a knife having its shank extending in a plane substantially parallel to the plane of the insole and having a cutting edge below the reinforcing fabric at the edge of the insole and operating 105 to sever the outer marginal portion of said fabric adhering to the face of the feather of the insole at the shank portion at least, substantially as described.

9. A machine for applying reinforcing 110 fabric to an insole, having, in combination, means for supporting and feeding the insole and for operating upon the reinforcing fabric 115 at its marginal portion, and a drag knife at the edge of the insole operating to trim the reinforcing fabric on the feather of the insole, at the shank portion at least, along a line spaced from the edge of the insole, substantially as described.

10. A machine for operating on a lipped 120 insole, having in combination, means for engaging opposite sides of the lip having co-acting faces operating to bend the lip inwardly into a hook having its upper portion substantially parallel to the face of the insole, and coöperating means for setting the bent lip in such position, substantially as described.

11. A machine for operating on a lipped 125 insole, having, in combination, tools at op- 130

posite sides of the lip for continuously and progressively engaging the lip and coöperating to bend the lip inward, and an ironing tool for setting the lip in the angular position toward which it is bent by the lip bending tools, substantially as described.

12. A machine for operating on a lipped insole, having, in combination, tools at opposite sides of the lip for continuously and progressively engaging the lip and coöperating to bend the lip inward, and an ironing tool operating on the bent lip subsequently to the lip bending tools for setting the lip in the angular position toward which it is bent by said lip bending tools, substantially as described.

13. A machine for operating on a lipped insole, having, in combination, a pair of rolls

at opposite sides of the lip having co-acting surfaces to bend the lip inward, and an ironing bar above the lip arranged to engage the bent lip and set it in the angular position toward which it is bent by said rolls, substantially as described.

14. In a machine for operating on a lipped insole, coöperating tools at opposite sides of and above the lip constructed and arranged to operate continuously and progressively along the lip to produce a right angular bend at the upper portion of the lip, substantially as described.
